(57) **CLAIM**

The ornamental design for a vehicle wheel, as shown and
described.

DESCRIPTION

FIG. 1 is a front perspective view of a vehicle wheel
embodying our new design;

FIG. 2 is a front elevation view thereof;

FIG. 3 is a rear perspective view thereof;

FIG. 4 is a rear elevation view thereof; and,

FIG. 5 is a side elevation view thereof, of which the
opposing side elevation view, top plan view and bottom plan
view are identical.
